(21) Appl. No.: **29/537,179**

The ornamental design for a medical pump bracket, as
shown and described.

(22) Filed: **Aug. 24, 2015**

DESCRIPTION

(30) **Foreign Application Priority Data**

FIG. 1 is a front view of a first embodiment of the medical
pump bracket;

Feb. 23, 2015 (CA) 161043

FIG. 2 is a rear view of the first embodiment of the medical
pump bracket of FIG. 1;

(51) **LOC (10) Cl.** **24-02**

FIG. 3 is a top view of the first embodiment of the medical
pump bracket of FIG. 1;

(52) **U.S. Cl.**

FIG. 4 is a bottom view of the first embodiment of the
medical pump bracket of FIG. 1;

USPC **D24/128**

FIG. 5 is a left side view of the first embodiment of the
medical pump bracket of FIG. 1;

(58) **Field of Classification Search**

FIG. 6 is a right side view of the first embodiment of the
medical pump bracket of FIG. 1;

USPC D24/111, 127-129, 227; D8/355, 373,
D8/394

FIG. 7 is a front view of a second embodiment of the
medical pump bracket;

CPC A61M 5/1415; F16M 13/02

FIG. 8 is a rear view of the second embodiment of the
medical pump bracket of FIG. 7;

See application file for complete search history.

FIG. 9 is a top view of the second embodiment of the
medical pump bracket of FIG. 7;

(56) **References Cited**

FIG. 10 is a bottom view of second first embodiment of the
medical pump bracket of FIG. 7;
